No. 722,714.

PATENTED MAR. 17, 1903.

J. KAHN.

HAIR COMB.

APPLICATION FILED DEC. 17, 1902.

NO MODEL.

UNITED STATES PATENT OFFICE.

JULIUS KAHN, OF WEEHAWKEN HEIGHTS, NEW JERSEY, ASSIGNOR TO
PACIFIC NOVELTY COMPANY, OF NEW YORK, N. Y., A FIRM.

HAIR-COMB.

SPECIFICATION forming part of Letters Patent No. 722,714, dated March 17, 1903.

Application filed December 17, 1902, Serial No. 135,478. (No model.)

To all whom it may concern:

Be it known that I, JULIUS KAHN, a subject of the Emperor of Germany, and a resident of Weehawken Heights, county of Hudson, 5 and State of New Jersey, have invented a certain new and useful Improvement in Hair-Combs, of which the following is a specification.

Heretofore in dressing the hair where a 10 pompadour effect has been sought a pad known as a "rat" has been used, over which the hair has been brushed and held in position by means of a comb with substantially straight teeth or by pins, &c.

15 It is the object of my invention to get the pompadour effect without the use of a rat, and this I accomplish by means of the peculiar shape given to the teeth and body of my comb, thus dispensing with the use of a rat 20 or the like, while the comb simultaneously performs in addition all of the usual functions of a comb.

25 For a more particular description of my invention reference is had to the accompanying drawings, forming a part of this specification, in which one embodiment of my invention is disclosed.

Figure 1 is a side or outer face view of my 30 improved comb. Fig. 2 is a plan view of the upper edge of the same. Fig. 3 is a section on the line 3 3 of Fig. 1 looking in the direction of the arrows. Figs. 4 and 5 are sectional views taken on the lines 4 4 and 5 5 of Fig. 1 looking in the direction of the arrows, 35 one tooth only being shown in each case.

Throughout the various views similar reference characters designate similar parts.

The comb comprises the usual back 1, to 40 which are attached or formed integral therewith the teeth or fingers 2. These fingers are curved or arched at 3 in substantially the arc of a circle, as shown in Figs. 2, 3, and 4, and near their outer extremities are straightened at 4, so as to be substantially a prolongation 45 of the back 1. These teeth in the preferred form vary in length and curvature from the center to the sides, those near the center being the longest and having the shortest straightened portion, and the adjacent teeth 50 vary but slightly both as to length and curvature, so that the arched portion of the teeth

appear to have the shape of a rat when the comb is shown in the positions of Figs. 1 and 2. It is obvious that any other desired curvature may be given to the teeth provided the 55 effect of a rat is maintained, and the length of the teeth and that of the curve or arch 3 may be varied and the latter made uniform in length from end tooth to end tooth without departing from the spirit of my invention. 60

The back 1 is preferably bent on the arc of a circle and may be made of any desired length, as these features vary with the use to which the comb may be put.

In using my improved comb it acts as follows: When the ends of the teeth 2 are inserted in the hair, the hair fills the spaces between the teeth and then spreads out over the arched portions 3. This action is assisted by the downward pressure of the back 1 70 against the hair, which also tends to force it over the arched portions 3, thus giving the pompadour effect without a rat. The comb is preferably inserted after the hair is otherwise arranged, and so can be used with much 75 less trouble than the rat, which must be worked into the hair as it is made up.

I am aware that hair-combs have been made prior to my invention in which there has been a slight yet uniform curve from the back 1 to 80 the tip of the teeth. So I do not claim, broadly, a comb with teeth having a curve.

What I do claim as my invention is—

1. A device of the character described having a back, teeth secured thereto and formed 85 with substantially straight ends connected to said back by means of outwardly-arched intermediate portions.

2. A device of the character described having a back, teeth secured thereto and formed 90 with substantially straight ends which form substantially a prolongation of said back and arched portions connecting said ends and back.

3. A device of the character described, having a back, teeth secured to said back of varying length and arched intermediate portions, said arched portions being reduced from the center of the comb to its ends.

4. A device of the character described, having a back, teeth secured thereto having outwardly arched or curved portions adjacent to

said back, said arch or curve extending beyond a line drawn from the back to the ends of the teeth.

5. A device of the character described, having a back, teeth secured thereto having outwardly arched or curved portions, the said curved portions being reduced in length from the center of the comb to its ends, said arch

or curve extending beyond a line drawn from the back to the ends of the teeth.

Signed in the city, county, and State of New York this 15th day of December, 1902.

JULIUS KAHN.
